UNITED STATES PATENT OFFICE.

WILLIAM WALKER, OF SEDALIA, MISSOURI, ASSIGNOR, BY DIRECT AND MESNE ASSIGNMENTS, OF ONE-THIRD TO SVEN P. ALQUIST, OF SEDALIA, MISSOURI, AND ONE-THIRD TO WILLIAM L. KELLOGG, OF PARSONS, KANSAS.

GRAIN-DOOR.

1,188,120.

Specification of Letters Patent. Patented June 20, 1916.

Application filed May 28, 1915. Serial No. 31,018.

To all whom it may concern:

Be it known that I, WILLIAM WALKER, a citizen of the Dominion of Canada, residing at Sedalia, in the county of Pettis and State 5 of Missouri, have invented certain new and useful Improvements in Grain-Doors, of which the following is a specification.

My invention relates to a sheet metal grain door for railway box cars.

10 One of the principal objects of the invention is to provide a grain door of this type which will be strong, inexpensive to manufacture, light in weight, and compact in its construction so that it will take up but little 15 space in the car.

A further object is to provide certain novel and improved means for mounting the door within the car whereby it may be readily put in position across the door opening, 20 when the car is to be loaded with grain, in such manner as to effectually prevent any leakage, and moved away from the door opening against the side wall of the car, so as to be entirely out of the way, when the 25 car is used for other kinds of freight.

My invention contemplates a grain door of the sort provided with a small relief door or slide which may be opened to allow the discharge of a certain amount of grain in 30 order that the pressure against the door may be relieved sufficient to allow the door as a whole to be moved away from the door opening; and in this connection the invention consists in certain improvements in the construction of the main door and of the relief 35 or sub-door whereby the latter may be readily manipulated and whereby the door structure as a whole will be compact, simple in its construction and little liable to become injured or get out of order with continued use.

40 The invention has for further objects such other new and improved constructions, arrangements and devices relating to grain doors for railway cars as will be hereinafter described and claimed.

The invention is illustrated in the accompanying drawings in a preferred embodiment, this embodiment being susceptible of modifications in certain respects, as will be 50 apparent to those skilled in the art.

Figure 1 is a fragmentary vertical, longitudinal section taken through a box car of ordinary construction showing the grain door of my invention in position across the

side door opening of the car; the view being 55 taken from the interior of the car. Figs. 2 and 3 are vertical sectional views taken on lines 2—2 and 3—3, respectively, of Fig. 1. Figs. 4 and 5 are fragmentary sectional plan views taken on lines 4—4 and 5—5, respectively, of Fig. 1, and Fig. 6 is a detail sectional view on line 6—6 of Fig. 1 illustrating the device arranged flush with the side wall of the car for holding the door in its open position, that is, when the door is slid away 65 from the door opening against the side wall of the car.

The detail views of Figs. 2 to 6 are all on a scale somewhat larger than that of Fig. 1. Like characters of reference designate like 70 parts in the several figures of the drawings.

The box car in connection with which the grain door of my invention is illustrated in the drawings, is a wood box car of standard type. The floor of the car is indicated at 10, 75 the roof at 11, the sheathing at 12 and the inner lining at 13. The side wall of the car is provided with the usual door opening 14 which may be closed by any suitable door, such, for example, as the sliding outside 80 door 15. The grain door of my invention is arranged within the side wall of the car and in closed position bears against the door posts 16, 17. The main door consists preferably of a sheet metal structure 18 pressed to 85 a dished configuration and formed with an upper marginal flange 19, a lower marginal flange 20, and a flange 21 at its forward edge. The upper marginal flange 19 enters a channel-shaped guide 22 secured to the 90 side wall of the car rearwardly of the door opening. A guide is also provided for the lower flange 20 consisting preferably of an angle iron 23 secured to the floor 10 of the car, the vertical leg of which lies close to 95 the inner lining 13. When the door is closed across the door opening 14 the flange 21 on the forward edge enters a channel-shaped keeper 24 on the door post 16. The rear edge of the door is formed with a 100 reversely extending flange 25 which enters a channel-shaped keeper 26 on the door post 17 when the door is in said closed position. Set into the side wall of the car so as to be flush with the lining 13 is a housing 27 held to the belt rail 28 by a bolt 29 (Fig. 5).

Pivotaly mounted within the housing is a staple 30 which may be turned on its pivot

- stud 31 so that it will project out of the housing in position to be engaged by a slotted hasp 32 hinged at 33 to the door 18 and by a hook 34 pivoted to the hasp. By this device the door is held in closed position. A similar housing 27^a is set into the side wall of the car at such distance from the door opening that the hasp and hook on the door may be engaged with the pivoted staple 32^a
- 10 when the door is moved through guides 22, 23 to a position entirely away from the door opening. The housing 27^a is shown (Fig. 6) as set into one of the uprights 35 of the car framing. Preferably a metal threshold strip 15 36 is laid across the floor at the door opening against which the flange 20 on the door bears when the door is in closed position.
- The main door is preferably dished inwardly of the car as shown. It is formed 20 with an opening 37. The relief door 38 which closes this opening is composed preferably of a piece of sheet metal which is pressed to a dish-shaped configuration and is arranged within the dished portion of the 25 main door. The relief door is provided with flanges 39, 40 on its upper and lower edges which extend into guides 41, 42 riveted to the outer face of the main door. The forward edge of the relief door has a flat marginal flange 43 which bears against the outer surface of the main door, when the small door is closed; and the rear edge of the 30 small door is provided with a reversely bent flange 44 which has an interlocking relation 35 with a reversely bent flange 45 on the main door at the rear edge of the opening 37. A slotted hasp 46 secured to the relief door by a staple 47 engages with a staple 48 on the main door. Any suitable device, such as a 40 car seal, may be employed for holding the hasp 46 in engagement with the staple 48.
- It will be seen that when the main door is 45 in position across the door opening 14 engagements are provided between the vertical edges and the lower edge of the door and the car which make the car absolutely grain-tight at these places. The fact that the door is dished inwardly gives it very considerable strength to withstand the thrust of the load.
- 50 The relief door has a grain-tight connection with the main door. At the same time it may be very easily slid away from the opening in the latter so as to relieve the pressure sufficiently to permit the main door to be 55 moved away from the door opening. The relief door, its guides, and the means employed for holding the door in closed position are arranged wholly within the dished portion of the main door so as to be entirely 60 out of the way when the main door is opened, while at the same time these parts are accessible from the outside of the car after the outside door 15 has been opened. The main door, it will be seen, is locked from 65 within so that it cannot be opened by an un-

authorized person. The relief door is protected from being tampered with by sealing the hasp 46 to staple 48. When enough grain has been discharged through the door opening in the main door to relieve the pressure against the latter, the door may be readily moved backwardly in guides 22, 23 so that the whole of the door opening in the side of the car will be available for discharging the bulk of the cargo. The door slides 70 over the fastening device 27, 30, the staple of which lies wholly within the housing 27 when released by the hook 34 and hasp 32. When the grain door is not in use it lies close up against the inside wall of the car so 80 as to take up very little room and, furthermore, so as to be entirely out of the way and not likely to be injured by the lading of the car.

While I have described my invention in 85 certain preferred embodiments, it will be understood that modifications might be made without departure from the principles of the invention. Therefore I do not wish to be understood as limiting the invention to the 90 particular constructions, arrangements and devices shown and described except so far as the claims are specifically so limited.

I claim:

1. A car having a door opening, in combination with a grain door of sheet metal, the center portion of which is pressed to a dished configuration with the dished part projecting into the interior of the car and with the marginal portion surrounding the central dished portion forming flanges, guiding means to receive said marginal flanges arranged on the inside of the car adjacent said opening, in which guiding means the door may be slid back and forth across the door 95 opening, said dished portion of the main door being formed with an opening, and a sub-door to close said opening which is located within the vertical planes defining the main door. 100

2. A car having a door opening, in combination with a grain door structure comprising a main door of sheet metal, the center portion of which is pressed to a dished configuration with the dished part projecting 110 into the interior of the car and with the marginal portion surrounding the central dished portion forming vertical flanges, guiding means to receive said marginal flanges arranged on the inside of the car adjacent said opening, in which guiding means the door may be slid back and forth across the door opening, said dished portion of the main door being formed with an opening, and a sub-door to close said opening which is located within the vertical planes defining the main door. 115

3. A car having a door opening, in combination with a grain door structure comprising a main door of sheet metal, the center 120

- portion of which is pressed to a dished configuration with the dished part projecting into the interior of the car and with the marginal portion surrounding the central dished portion forming vertical flanges, guiding means to receive said marginal flanges arranged on the inside of the car adjacent said opening, in which guiding means the door may be slid back and forth across the door opening, said dished portion of the main door being formed with an opening, and an oppositely dished sheet metal sub-door to close said opening located within the vertical planes defining the main door.
4. A car having a door opening, in combination with a grain door structure comprising a main door of sheet metal, the center portion of which is pressed to a dished configuration with the dished part projecting into the interior of the car and with the marginal portion surrounding the central dished portion forming vertical flanges, guiding means to receive said marginal flanges arranged on the inside of the car adjacent said opening, in which guiding means the door may be slid back and forth across the door opening, said dished portion of the main door being formed with an opening, guides on opposite sides of said opening and within the dished portion of the door, and an oppositely dished sub-door located within the vertical planes defining the main door
- formed with marginal flanges slidable in said guides.
5. A grain door structure comprising a main sheet metal door, the center portion of which is pressed to a dished configuration with the marginal portion surrounding the central dished portion forming flanges lying in the same plane so that they may bear flatwise against the door frame of the car, the dished portion of said main door being formed with an opening, and a sub-door to close said opening which lies within the dished portion of the main door.
6. A grain door structure comprising a main sheet metal door, the center portion of which is pressed to a dished configuration with the marginal portion surrounding the central dished portion forming flanges lying in the same plane so that they may bear flatwise against the door frame of the car, the dished portion of said main door being formed with an opening, guides on opposite sides of said opening within the dished portion of the main door, and an oppositely dished sub-door located within the vertical planes defining the main door having flanges slidable within said guides.
